STORAGE BOX

Irwin J. Ferdinand, Glencoe, and Irwin R. Kulbersh, Morton Grove, Ill., assignors to The Hirsh Company, Skokie, Ill.

Filed Mar. 16, 1970, Ser. No. 21,918

Term of patent 3½ years

Int. Cl. D3—99

U.S. Cl. 87—1

FIG. 1 is a perspective view of a storage box showing our new design;

FIG. 2 is a perspective view thereof with the box lid raised;

FIG. 3 is a perspective view thereof showing the bottom thereof;

FIG. 4 is a front elevational view thereof; and

FIG. 5 is a side elevational view thereof, the other side of the storage box being a mirror image thereof.

We claim:

The ornamental design for a storage box, as shown and described.
